UNITED STATES PATENT OFFICE

JOHN E. LUDWIG, OF DETROIT, MICHIGAN, ASSIGNOR TO NEWCOMB-DAVID COMPANY, INC., OF DETROIT, MICHIGAN, A CORPORATION OF MICHIGAN

PNEUMATIC CONVEYER

Application filed October 29, 1928. Serial No. 315,649.

The present invention pertains to a novel pneumatic conveyer for the purpose of carrying material such as shavings, dust and waste away from working machinery and discharge it at some suitable point.

The principal feature of the invention resides in the fact that the movement of material through the conveyer is produced not only by suction means at the discharging end or pressure means at the opposite end, but also by a device for throwing air into the conveyer proper at intermediate points thereof in the direction of discharge. Such a construction is obtained by building the conveyer proper of sections joined together telescopically, providing an opening in each joint, securing a conduit to the conveyer proper in a manner to communicate with these openings, and blowing air into the conduit in the direction of discharge. An exhaust fan is provided at the discharge end of the conveyer proper for drawing the material therethrough, and the movement of the material is obviously assisted by the air that is charged into the conduit.

The invention is fully disclosed by way of example in the following description and in the accompanying drawings in which—

Figure 1 is a side elevation of the apparatus;

Fig. 2 is a fragmentary longitudinal section thereof on an enlarged scale; and

Fig. 3 is a transverse section on the line 3—3 of Fig. 1.

Reference to these views will now be had by use of like characters which are employed to designate corresponding parts throughout.

In Fig. 1 the conveyer proper is illustrated as being comprised of a number of sections 1 each having one end 2 received in an adjacent section and its other end 3 receiving the other adjacent section. The receiving end is somewhat enlarged as at 4 through a comparatively short extent of its perimeter to form an opening 5 between the enlargement and the received end 5 adjacent thereto. The openings are preferably formed in alignment at the lowest point of the conveyer conduit.

A conduit 6 consisting also of telescopically

joined sections is supported preferably beneath the conveyer proper in such a manner as to enclose the openings 5 and thereby communicate with them. The conduit is of channel cross section as clearly shown in Fig. 3 and 55 is secured to the conveyer proper by means of marginal flanges 8 riveted as at 9 to the sections 1.

At the discharge end of the conveyer proper constituted by the sections 1 is provided an exhaust fan or blower 10 for drawing material through the sections 1 and discharging it. The sections 1 may be tapped as at 11 at selective points in order to communicate with branches leading from various machines. At the opposite end of the conduit 6 is provided a fan or blower 12 for charging air into the conduit in the direction towards the fan 10. The air from the fan 12 obviously enters the sections 1 through 70 the openings 5 and assists in carrying the material to the point of discharge.

Although a specific embodiment of the invention has been illustrated and described, it will be understood that various alterations in the details of construction may be made without departing from the scope of the invention as indicated by the appended claim.

What I claim is:—

A pneumatic conveyer comprising an enclosed main conduit having permanently free openings in the bottom thereof, said main conduit having a series of apertures for connection of branch intakes thereto, an air conduit secured to said main conduit in a manner to enclose said openings and communicate therewith, and means for forcing air into said air conduit.

In testimony whereof I affix my signature,

JOHN E. LUDWIG
